LATHE GRINDER

Joseph W. Kock, Cranford, N. J.

Application October 22, 1952, Serial No. 316,168

3 Claims. (Cl. 51—259)

1

This invention relates to lathe grinders, and more particularly to motorized attachments for metal-turning or screw-cutting lathes to adapt them for various grinding operations, particularly of the heavy duty type.

The conventional lathe grinder attachment comprises an abrasive wheel mounted directly on the shaft of a small electric motor of generally fractional horsepower, the frame of the motor being mounted on the compound slide of the lathe, for example, by a bar entering the tool post on the compound slide. Inasmuch as the abrasive wheel is mounted close to the motor casing, this direct mounting seriously limits the depth of internal grinding possible and the adaptability of external grinding, and subjects the motor parts to excessive abrasive dust, as well as throwing the strain of the grinding force on the bearings of the motor. Furthermore, for heavy duty grinding requiring a large size motor such as one or more horsepower, the weight of the motor is difficult for the operator to lift, transport and install, and also throws a strain on the compound slide of the lathe.

While some belt drives for grinding attachments have been provided, these have generally required the motor to be mounted on the compound slide of the lathe and have involved excessive power losses. Also, such belt drives have not been flexible in adaptation to various required operations, and have been inoperative or limited in depth for internal grinding.

To increase the depth of internal grinding by providing motor shaft extensions has required the provision of graded lengths of extensions, time consumed in coupling, and difficulty of preserving alignment, rendering precision grinding difficult if not impossible.

Objects of the present invention are therefore to avoid the difficulties of direct drive of the grinder wheel, shaft extensions, and belt drives. Other objects are to avoid the lifting of heavy motors and facilitate setting up the grinder, to increase the depth of operation for internal grinding and the flexibility of adaptation of the grinder to various operations; to increase the stability of the bearing support for the grinder shaft and provide for precision grinding; to increase the capacity and clearance of the compound slide of the lathe, to remove the motor from the region of excessive abrasive dust, and to avoid strain on the motor bearings and on the compound slide of the lathe.

According to the present invention, a grinder shaft is rigidly but adjustably journaled on the

2

lathe compound slide, and coupled to a flexible shaft from a source of power supported independently of the slide. The grinder shaft is journaled in a long barrel having bearings at each end, the long distance therebetween insuring steady rotation. The barrel is adjustably mounted in a clamp comprising a split sleeve mounted in a rigid frame. The length of the barrel provides a deep range of adjustment for internal grinding. The rigid frame has a large base area engaging the top of the compound slide to insure a rigid mounting, and is adjustably secured thereto by a bolt received in the tool post slot of the compound slide. The split sleeve adjustably receives the barrel, and is locked in position by set screws on the frame compressing the split sleeve. A rigid brace is clamped to the rear end of the barrel and extends over the coupling and is clamped to the handpiece of the flexible shaft to prevent vibration of the coupling.

Other objects and features of novelty will be apparent from the following description and the accompanying drawings, in which:

Fig. 1 is a perspective view of a metal-turning or screw-cutting lathe having installed thereon the grinder attachment according to the preferred embodiment of the present invention;

Fig. 2 is a horizontal section through the grinder shaft mounting; and

Fig. 3 is a vertical section taken along the line 3—3 of Fig. 2.

Referring more particularly to the drawings, in Fig. 1 the invention is illustrated as being mounted on a conventional metal-turning or screw-cutting lathe, comprising a headstock 10, ways 12 and 14 and a tailstock 15. The headstock spindle is driven by a suitable source of power, such as stepped pulleys 16 and a belt 17, and is provided with a chuck 18 which grips the workpiece 20.

The ways 12 and 14 slidably support a carriage 22 which may be advanced by a feed screw 23 suitably geared to the headstock drive, or manually advanced by a handle 25. The carriage 22 slidably supports a cross-slide 26 which may be advanced by a handle 27. Pivoted on the cross-slide 26 is a compound base 30 on which is mounted a compound slide 32 moved radially of the pivot by a handle 33. The compound slide 32 has a transverse undercut slot 34 adapted to receive the bottom of the conventional tool post not shown.

According to the present invention, in place of the usual tool post, a belt 35 is provided, having a head 36 slidable in the tool post slot 34

for securing to the compound slide the clamp for mounting the grinder shaft. This clamp comprises a rigid frame 37 having upper and lower plates 38 held in spaced relation by spaced posts 39, forming a rigid frame having lightness for handling as well as strength for rigidly supporting the grinder shaft.

The plates 38 have registering slots 40 receiving the bolt 35, and the lower plate 38 has a large bearing area engaging the top of the compound slide 32 to provide a firm mounting when the nut 41 is tightened. The slots 40 permit adjustment of the frame along the slots, in effect increasing the range of the tool post slot 34, and also permitting pivoting of the frame about the bolt 35 in any position thereof as a universal adjustment, in effect also increasing the range of the compound slide 32.

The plates 38 extend beyond the posts 39 and receive therebetween a split sleeve 42, which is square in external cross section, and has a cylindrical central bore which slidably receives a grinder shaft supporting barrel 43 clamped thereby and locked in adjusted position by set screws 44 in the upper plate 38.

The barrel 43 comprises a long rigid tube having a thrust bearing 45 near the abrasive wheel end, and rotary antifriction bearings 46 near each end, protected by dust excluding and grease retaining rings 47, and journaling a grinder shaft 48 having secured to one end thereof an abrasive wheel 49. The long distance between the bearings 46 provides a steady journal for the grinder shaft, and the long axial dimension of the barrel 43 provides a large range of depth adjustment for internal grinding of deep cavities in workpieces.

The end of the grinder shaft opposite from the wheel end thereof, extends out of the rear end of the barrel 43, and is connected by a coupling 50 to the driven end of a flexible shaft 52 comprising a casing 53 including a handpiece 54. The driving end of the flexible shaft is connected by a coupling 55 to the shaft of an electric motor 56 which may be of one or more horsepower, and supported independently of the lathe compound slide, for example by a portable table 57 having casters 58 resting on the shop floor.

In order to prevent whipping or vibration of the coupling 50 a rigid brace is provided, comprising a split sleeve clamp 60 mounted on and gripping the rear end portion of the barrel 43, a split sleeve clamp 62 mounted on and gripping the handpiece 54, and a rigid bridge plate 63 secured to the barrel clamp 60, extending over the coupling 50, and secured to the handpiece clamp 62. Thus the handpiece bearing is rigidly secured in alignment with the barrel bearings.

When not in use, the grinder attachment may be stored with or hung on the wheeled table 57 which carries the motor 56. The flexible shaft 52, coupling 50, brace 63, barrel 43, clamp 42 and frame 37 may remain assembled.

When it is desired to set up the device for operation, the table 57 is wheeled into position adjacent to the lathe, the tool post removed, and the attachment bolt head 36 is inserted in the tool post slot 34 of the lathe compound slide 32. The bolt 35 is positioned along the slot 34, and the frame 37 is positioned angularly about the bolt 35 and along the frame slot 40 to give the best bearing on the compound slide 32 to suit the particular operation on the workpiece 20, after which the nut 41 is tightened to secure the

frame 37 firmly in position on the compound slide 32.

The barrel 43 is then slid along inside the split sleeve 42 to extend the abrasive wheel 49 the desired distance for the depth of the cavity in the workpiece 20, after which the barrel 43 is locked to the frame 37 by the set screws 44 engaging and constricting the split sleeve 42. After the motor 56 is started, the abrasive wheel 10 may be advanced into the work by the feed screw 23, or manually by the carriage handle 25 or the compound slide handle 33.

When it is desired to set up for a different depth or shape of workpiece, the set screws 44 15 may be loosened and the barrel 43 slid along inside the split sleeve 42, or the nut 41 may also be loosened for universal adjustment of the frame 37. This involves no interference with the drive, because the flexible shaft 53 follows the 20 sliding of the barrel and the universal adjustment of the workpiece. To avoid too sharp curvature of the flexible shaft 53 the wheeled table permits the motor 56 to be moved to a position requiring less curvature.

I claim:

1. A lathe grinder for attachment to a lathe having a compound slide and adapted to be driven by a flexible shaft from a source of power supported independently of said lathe, said flexible shaft having its driving end provided with a handpiece, comprising a rigid grinder shaft adapted for the mounting of an abrasive wheel on the driving end thereof, a barrel having axially spaced bearings journaling said grinder shaft, a clamp having means for securing said shaft bearing barrel to the lathe compound slide, a coupling between the driven end of said rigid grinder shaft and the flexible shaft, and a rigid brace secured to said shaft bearing barrel and extending beyond the coupling and secured to the handpiece of said flexible shaft.

2. A lathe grinder for attachment to a lathe having a compound slide and adapted to be driven by a flexible shaft from a source of power supported independently of said lathe, comprising a rigid frame adapted to be mounted on the lathe compound slide and having upper and lower plates and spacers holding said plates apart, said plates extending laterally beyond said spacers, a barrel between said plate extensions of greater length than the width of said extensions, bearings in said barrel axially spaced a distance greater than the width of said extensions, a rigid grinder shaft journaled in said barrel and having a driven end projecting therefrom adapted to receive an abrasive wheel and a driven end adapted to be coupled to the driving end of said flexible shaft, means on said upper plate extension for locking said barrel in position, the axial spacing of said bearings and the length of said barrel permitting said barrel to be unlocked and moved axially between said extensions to adjust the position of said wheel toward and away from said slide.

3. A lathe grinder for attachment to a lathe having a compound slide and adapted to be driven by a flexible shaft from a source of power supported independently of said lathe by a flexible shaft having a handpiece at its driving end; comprising a rigid grinder shaft adapted for the mounting of an abrasive wheel on the driving end thereof, a barrel having axially spaced bearings journaling said grinder shaft, a clamp having means for securing said shaft bearing barrel to the lathe compound slide, a coupling between the

driven end of said rigid grinder shaft and the driving end of said flexible shaft, a rigid brace secured to said shaft bearing barrel and extending beyond said coupling and secured to the handpiece of said flexible shaft, an electric motor coupled to the driven end of said flexible shaft, and a portable table on which said motor is mounted and having casters for engaging the shop floor.
